CLAIM

The ornamental design for a facsimile machine, as shown and described.

DESCRIPTION

FIG. 1 is a front, top and right side perspective view of a facsimile machine, showing our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof; and,

FIG. 8 is a front, top and right side perspective view of a second embodiment of the facsimile machine.

The undisclosed views of the second embodiment (FIG. 8) are same as disclosed in FIGS. 2-7 of the first embodiment (FIG. 1).
